UNITED STATES PATENT OFFICE.

ANDREW H. MILLER, OF DETROIT, MICHIGAN.

ELECTRIC SWITCH FOR ELECTRIC LAMPS AND THE LIKE.

1,150,001.

Specification of Letters Patent. Patented Aug. 10, 1915.

Application filed May 10, 1906. Serial No. 316,180.

To all whom it may concern:

Be it known that I, ANDREW H. MILLER, a citizen of the United States, and a resident of Detroit, county of Wayne, and State of Michigan, have invented certain new and useful Improvements in Electric Switches for Electric Lamps and the like, of which the following is a specification.

The invention relates to an improved automatic flashing switch for use in connection with the electric lamps of a sign, or with other electrically operated advertising devices.

The invention seeks to provide a simple and effective form of flashing switch by which the intensity of the lamps can be automatically dimmed and intensified or other electrical devices automatically operated.

Further objects of the invention are to provide a thermostatic flashing switch in which a single switch member of homogeneous metal or alloy can be employed in place of the usual two-metal thermostat, and to provide an automatic flashing switch which may be economically manufactured, which can be readily adjusted and which will not readily get out of order or out of adjustment or be affected by vibration.

With these objects in view the invention consists in the features of construction, combinations and arrangements of parts hereinafter set forth, illustrated in the accompanying drawings and more particularly pointed out in the appended claims.

In the drawings, Figure 1 is a diagram illustrating the manner of connecting the improved switch to a number of lamps forming a sign. Fig. 2 is a plan of the improved switch. Fig. 3 is a view partially in elevation and with parts shown in section on the line 3—3 of Fig. 2. Fig. 4 is a cross section on the line 4—4 of Fig. 3.

Advertising signs and the like containing a number of electric lamps have usually been flashed up and down by expensive motor driven switch mechanism.

The present invention provides a simple thermostatic device, the thermostatic switch member of which is preferably in the form of a single homogeneous strip of metal by which one or a number of lamps or like devices can be intermittently turned on or off.

As shown a series of lamps 10 arranged to form the letters of a sign, or in any other

suitable manner, are connected in parallel with the line wires 11 and 12. Line wire 11 is connected to one pole of the battery 13 or other source of current, the other pole of which is connected to one terminal of the switch by wire 14. Line wire 12 is connected to the other switch terminal.

The flashing switch is mounted upon a base-board 15 of stone, glass or other suitable material, and comprises a thermostatic switch member in the form of a bent strip or bow 16, rigidly secured at its ends to the base 15 by bolts or binding screws 17. The ends of the strip are arranged between washers 18 on the bolt and nuts 19 thereon firmly connecting the parts together.

The bent strip or bow 16 is formed of any desirable homogeneous metal or alloy that is highly expansible by heat. Its ends are firmly anchored in position, as described, so that the expansion thereof will cause an outward movement of its central portion which is provided with a button or contact 20. The thermostatic switch member or strip 16 is covered, except at its ends and except the centrally projecting button or contact 20, with suitable insulating material 21 such as mica, vulcanized fiber or the like, and upon this insulating cover is wound a heating coil 22. The heating coil for the thermostatic switch member is of very small size and of high resistance and comprises a large number of turns. This heating coil is preferably formed of German silver or other suitable high resistance material.

A metal conducting strip 23 of brass or like material, is centrally secured to the base 15 by a bolt or binding screw 24, which extends through the base at one side of and adjacent the central portion of the bent strip or bow 16. The conducting strip 23 is bent upwardly and extends over the central portion of the thermostatic switch member or bow 16, and a contact screw 25 is adjustably threaded through the metal strip 23 above the button or contact 20 on the thermostatic switch member. A lock nut 26 holds the screw contact 25 in adjusted position.

In the form shown, contact 25 is normally out of engagement with contact 20 and the expansion of the bow 16 under the influence of the heat of the coil, brings the contacts of the switch into engagement. If desired, the contact could be arranged upon the opposite

side of the switch member so that the movement thereof, when heated, would disengage the contacts.

Battery wire 14 is preferably connected 5 to the binding screw 24 and conducting strip 23 by a washer 27 and nut 28 on the binding screw 24. The line wire 12 is connected to the binding screw 17 at one end 10 of the thermostatic switch member 16 by washer 29 and nut 30. One end of the heating coil 22 is connected to the binding screw 17 at the opposite end of the thermostatic switch member or bow 16 and the other end 15 of the coil is connected by a wire 31 to the binding screw 24, such wire being held in place on the screw by washer 32 and nut 33.

With the connections as described, current will normally flow from the battery 13 or other source of power, through wire 14, 20 binding post 24 and wire 31, through the heating coil 22 to one end of the bent thermostatic strip 16, thence through the strip 16 on the line wire 12, through the lamps of the sign and back by line wire 11 to the battery. The heating coil is thus in series with 25 the lamps and its relative resistance is so high that the amount of current passing through the circuit will be insufficient to light the lamps. The current flowing 30 through the circuit however, will be sufficient to heat the coil 22 and thermostatic switch member 16, so that the latter will expand and its central portion moved outwardly until the contact 20 is brought into 35 engagement with the contact 25. Upon such engagement, a low resistance shunt is formed around the heating coil and the current will flow from battery 13 or other source of power, by line wire 14, binding post 24, conducting strip 23 to the engaged contacts 25 and 20, thence by the strip 16, binding post 17, line wire 12 to the lamps of the sign and back as before by line wire 11 to the battery. The low resistance circuit thus formed permits a lighting current to pass and the 40 lamps of the sign will flash out brightly. But, inasmuch as the resistance of the coil 22 is very high compared to that of the circuit formed when the contacts are in engagement, only a small amount, or practically no current, will flow through the heating coil and the latter and the bow or thermostatic strip 16 will cool, and when the latter is contracted sufficiently, the engage- 45

ment between contacts 25 and 20 will be 55 broken so that the heating coil is again interposed in the circuit to cut down the current flowing and the lamps will be dimmed or become entirely dark.

It is obvious that numerous changes may 60 be made in the details of structure without departure from the essentials of the invention set forth.

Having described my invention, what I claim as new and desire to secure by Letters 65 Patent, is:

1. In an automatic flashing switch, the combination of an insulating base, a thermostatic switch member comprising a homogeneous bowed metal strip, terminal binding posts rigidly securing the ends of said bowed metal strip to said base, a conducting support, a terminal binding post securing said support to said base, said bowed metal strip having a contact on its outer face, a 70 normally fixed, adjustable contact on said support arranged to coöperate with the contact on said bowed metal strip, circuit conductors connected to said support and to one of the terminals of said strip, and a heating 75 coil wound about said bowed metal strip and connected at its ends to the other terminal thereof and to said conducting support, substantially as described.

2. The combination with one or more electric lamps, of an automatic flashing switch interposed in the circuit of said lamps and comprising an insulating base, a thermostatic switch member in the form of a homogeneous, bowed metal strip, terminal binding posts rigidly securing the ends of said strip to said base, a conducting support on said base, a normally fixed contact adjustably mounted on said support, said thermostatic switch member having a contact on its 90 outer face arranged to coöperate with said normally fixed adjustable contact, and a heating coil of relatively high resistance coiled about said switch member, said switch member, in closed position, being arranged 95 to form a shunt of relatively low resistance around heating coil, substantially as described.

ANDREW H. MILLER.
